UNITED STATES PATENT OFFICE.

PETER S. HOE, OF NEW YORK, N. Y., ASSIGNOR TO R. HOE & CO., OF SAME PLACE.

IMPROVEMENT IN PRINTERS' COMPOSING-STICKS.

Specification forming part of Letters Patent No. 132,722, dated November 5, 1872.

To all whom it may concern:

Be it known that I, PETER S. HOE, of the city, county, and State of New York, have invented an Improved Printer's Composing-Stick, of which the following is a specification:

Nature and Objects of the Invention.

My invention relates to printers' composing-sticks; and has for its object to produce a cheaper, stronger, and better-finished article than has heretofore been made, as will be set forth hereafter.

Description of the Drawing.

Figure 1 is a view of the blank from which the stick is made. Fig. 2 is a top view of the stick.

General Description.

The blank A is struck from suitable sheet metal by dies of the proper shape, the holes for adjusting the gage being formed in it by the same operation. The blank is then polished on both sides, and, thus prepared, the

pieces a^1 a^2 that are to constitute the sides of the stick are turned up at right angles to the bed of it by a die or other suitable means. To form a smooth and neat joint, and give the corner of the stick strength, the end b of the side a^1 projects slightly beyond the side a^2 when both are turned up, and this end is then beveled off, bent over, and soldered to the side a^2 , as seen at Fig. 2, b. This is the most desirable way of forming the joint, although it may be made immediately on the corner of the stick without lapping. The gage and clamping-screw are like those ordinarily used in composing-sticks, as will be readily understood from the drawing.

Claim.

As a new and improved article of manufacture a printers' composing-stick, the sides and bottom of which are formed from a single piece of sheet metal, substantially as described and specified.

PETER S. HOE.
